CLAIM

The ornamental design for a mixing bowl assembly for a stand mixer, as shown and described.

DESCRIPTION

FIG. 1 is a perspective view of a mixing bowl assembly for a stand mixer according to the design;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof; and,
FIG. 7 is a bottom plan view thereof.

The portions of the article shown in broken line form no part of the claimed design.

1 Claim, 7 Drawing Sheets

Related U.S. Application Data

No. 29/830,537, filed on Mar. 14, 2022, now Pat. No. Des. 986,678, which is a continuation-in-part of application No. 29/803,735, filed on Aug. 16, 2021, now Pat. No. Des. 1,011,843, which is a continuation-in-part of application No. 17/352,710, filed on Jun. 21, 2021.
